Patented Feb. 20, 1917.

UNITED STATES PATENT OFFICE.

ANTHONY F. WILLIAMS AND EDWARD A. HALBLEIB, OF ROCHESTER, NEW YORK,
ASSIGNORS TO NORTH EAST ELECTRIC COMPANY, OF ROCHESTER, NEW YORK, A
CORPORATION OF NEW YORK.

ELECTRIC SWITCH.

1,216,386.

Specification of Letters Patent. Patented Feb. 20, 1917.

Application filed April 22, 1915, Serial No. 23,236. Renewed January 9, 1917. Serial No. 141,496.

To all whom it may concern:

Be it known that we, ANTHONY F. WILLIAMS and EDWARD A. HALBLEIB, citizens of the United States, and residents of Rochester, in the county of Monroe and State of New York, have invented certain new and useful Improvements in Electric Switches, of which the following is specification.

This invention relates particularly to electric switches such as are employed in connection with electric currents which are of sufficient volume to produce harmful arcing or heating, and in which, accordingly, it is desirable to make provision, either by a snap-action or otherwise, for diminishing such effects.

One object of the invention is to so form and move the circuit-controlling contacts that any heating or arcing which occurs between them shall not be localized on the contact-members, but shall be distributed over surfaces of an area which is great in comparison with the current conducted. To this end we employ contact-members having wide contact-surfaces, and instead of causing these surfaces to be engaged and disengaged by the usual wiping action, we employ a mechanism for moving one of the contact-members toward and from the other in a direction at an angle to the contact-surfaces, while holding these surfaces parallel. In this manner the arcing is not confined to the edges of the contact-members, as in switches where they have a sliding or wiping engagement and disengagement, but is distributed over surfaces of wide area which are equidistant at all points at the moment when the arc is drawn. By the same arrangement the closure of the circuit occurs by the engagement of the contact-members over wide surfaces.

To further distribute the effects of arcing over the contact surfaces we employ an arrangement such that the movable contact-member, in addition to its circuit-controlling movement, has a more or less free independent rotative movement by which the parts of its contact-surface which engage any particular points of contact on the fixed contact-member may be constantly changed, thus distributing wear equally over

the contact-surfaces. This is conveniently accomplished, in the preferred embodiment of the invention, by imparting to the movable contact-member a helical, or combined 55 rotative and axial movement, toward and from the fixed contact-member, and by permitting the movable contact-member, in addition, a free independent rotative movement.

Another object of the invention is to provide, in a simple and effective manner, for giving the movable contact-member a sudden or snap-action in both closing and opening the circuit, and for this purpose we employ actuating-means comprising a spring which is connected, at one end, to an eccentric point on the means by which the movable contact-member is rotated, and at the other end to a manually-operable member arranged to swing the spring alternately to one side or the other of the axis of rotation of the movable contact-member.

Another object of the invention is to produce a switch in which the operative members shall be incased, but in which the several parts may be conveniently assembled in coöperative relation while open to inspection. For this purpose we employ an arrangement in which the casing of the 80 switch is in two parts, and in which the contact-members are assembled, as an operative organization, on one part of the casing, and the actuating-mechanism is assembled, as an operative organization, on the other part of 85 the casing, so that when the two parts of the casing are separated these two organizations are both complete in themselves, and therefore conveniently subject to adjustment or to inspection of their operation.

In the accompanying drawings:

Figure 1 is a vertical median section of a switch embodying the present invention, with the movable parts shown in an intermediate position to bring them into the section-plane;

Fig. 2 is a horizontal section on the line 2-2 in Fig. 1;

Fig. 3 is a horizontal section on the line 3-3 in Fig. 1, with some of the principal 100 parts broken away to show the parts below;

Fig. 4 is a partial plan-view of the switch,

with certain parts broken away to show the interior construction;

Fig. 5 is a detail-view, in vertical section on the line 4—4 in Fig. 3, showing a part of the means for securing the fixed contact-members in place; and

Fig. 6 is a perspective view of the stud by which the movements of the movable contact-member are directed.

The invention is illustrated as embodied in a switch having a casing comprising a plate or cover 10 and a hollow body 22. The plate 10 constitutes a base or support for the fixed contact-members, and for the means by which the movable contact-member is held in coöperative relation with the fixed contact-members. The fixed contact-members are shown as two in number, and they comprise circular curved members 11 and 12, which together constitute an annulus divided at two diametrically opposite points. Each fixed contact-member is provided, at the middle, with a binding-post 13, which extends through, but is insulated from the base-plate 10 and constitutes means for both securing the contact-member to the base-plate and connecting it with circuit-wires.

At their adjacent ends the fixed contact-members are secured in place, as shown in Fig. 4, by means of rivets 14, which have heads seated in recesses in the ends of the contact-members and acting to clamp these ends to the base-plate, insulation being interposed, however, between the rivets and the contact-members.

The movable contact-member is in the form of a flat disk 15. This disk is carried by a sleeve 16 which slides and rotates on a stud 17 fixed to the base-plate 10. The stud is provided, as shown in Fig. 5, with pins 18 which are helically arranged so as to engage corresponding helical slots in the inner surface of the sleeve 16. When the sleeve is turned upon the stud it consequently has a helical motion thereon, which motion is transmitted to the movable contact-member, so that this member, while held with its flat lower contact-surface always parallel with the flat upper contact-surfaces of the fixed members, moves toward and from the latter with a helical movement. The movable contact-member is connected with the sleeve 16 by an insulating spool 19, and it is fitted in the spool with sufficient looseness to permit a free rotation of the contact-member with respect to the sleeve.

It will be apparent that when the movable contact-member is engaged with, or disengaged from, the fixed contact-members this occurs not at any isolated points of the contact-members, but simultaneously throughout wide areas of contact, so that any arcing which occurs is distributed to such an extent as to have little or no harm-

ful effect. It will also be apparent that the provision for free rotative movement of the contact-member 15 permits this member to rotate indefinitely, in consequence of vibrations or of the opening and closing movement of the switch, in such a manner as to bring new points into engagement with any definite points on the fixed contact-members, thus distributing equally over the contact-surfaces such wear as may occur. Since the movable contact-member is supported in its middle portion, it is also capable of such minute rocking movements as may be necessary to insure that it shall always bear firmly upon both fixed contact-members when engaged therewith, and thus act to close the electric circuit by forming a path for the current between the two fixed contact-members.

The movable contact-member is slotted radially and is formed of thin and resilient sheet-metal, so that in case any roughness occurs at any particular point in either of the contact-surfaces, or any particle of foreign matter is interposed between the contact-members, one or more of the segments of the movable contact-member may yield independently and thus permit the proper seating of the rest of the segments.

The insulating spool 19 is fixed on the sleeve 16 between a collar 20 and a sheet-metal plate 21, which are both firmly secured to the sleeve, the plate 21 embracing a squared portion on the sleeve, as shown in dotted lines in Fig. 2. The plate 21 constitutes means for connecting the sleeve 16 with the manually-operable actuating-mechanism of the switch. This actuating-mechanism is mounted on the body 22 of the casing. Journaled in the top of the casing is a short rock-shaft 23, to the outer end of which is fixed an operating-arm 24. This arm embraces a squared portion on the rock-shaft, and by removing the arm and turning it to any of the eight different positions in which it may be placed on the shaft, the arm may be set in any convenient position for operation in accordance with the particular installation with which the switch may be used.

Upon the lower end of the rock-shaft 23 is fixed a sheet-metal member 25, and a spiral spring 26 is interposed between this member and the casing, the inner end of the spring being secured to the casing, as shown in Fig. 1, while the outer end is secured to the member 25, as shown in Fig. 3. This spring tends to return the rock-shaft and the operating-arm to the position of Fig. 3, in which the arm engages a stop 27, shown in Fig. 6.

The member 25 has a depending lug 28, to which is attached one end of a coiled tension-spring 29. The other end of this spring is attached to the middle portion of a U-

shaped rocking-member having upper and lower arms 30 and 31, as shown in Fig. 1. The upper arm 30 is loosely pivoted on a stud 32 projecting integrally from the lower end of the rock-shaft 28, while the lower arm 31 is loosely pivoted on a stud 33, which is seated in an opening in a cross-bar 34. This cross-bar is secured, at its ends, to lugs 35 projecting inwardly from the body of the casing. The stud 33 is also seated in an opening in the upper end of the stud 17, to insure assembling of the parts in the proper coaxial relation.

The U-shaped rocking-member is adapted to swing about its pivots through an angle limited by its engagement with two stop-lugs 36 and 37 in the body of the casing. This swinging movement is produced by the tension of the spring 29. In the normal position of the parts, shown in Figs. 2 and 3, the spring 29 extends in a line at one side of the axis of pivotal movement of the U-shaped member, but when the operating-arm is swung to its other position, as shown in Fig. 6, the spring 29 is swung to the opposite side of this axis, and as soon as it has passed the axis its tension causes the rocking-member to be at once swung to the position shown in Fig. 6. When the operating-arm is permitted to return to its normal position, under the influence of the spring 26, the spring 29 has the opposite effect on the rocking-member.

To transmit the movements of the rocking-member to the plate 21 and the sleeve 16, a depending lug 38 is provided at the end of the arm 31, which engages a forked extremity 40 on the plate 21. A similar lug 39 is punched out and bent downwardly from the rocking-member at the opposite side of its pivotal axis, this lug engaging the opposite forked extremity of the plate 21, and in this manner the rocking movements are transmitted to the sleeve 16, with the results previously described.

The plate 10 is fixed to the body of the casing by screws or in any convenient manner. When this plate is removed it carries with it the stud 17, the sleeve 16, and the movable contact-member, so that these parts remain as an assembled organization, while, on the other hand, the actuating-mechanism, including the rocking-member 30, 31, remains assembled within the body of the casing. The operation of either of these mechanisms may therefore be inspected, and any required adjustments made, with the parts of each organization in their co-operative relation. When the plate is replaced on the body of the casing the operative connections between the two organizations are conveniently effected by the introduction of the lugs 38 and 39 into the forked ends of the plate 21.

Our invention is not limited to the em-

bodiment thereof hereinbefore described and illustrated in the accompanying drawings, but it may be embodied in various other forms within the nature of the invention as it is defined in the following claims.

We claim:—

1. An electric switch having, in combination, an actuating-member; means for imparting a helical movement to the actuating-member; a contact-member carried by the actuating-member and having a contact-surface normal to the axis of movement of the actuating-member; and a fixed contact-member having a contact-surface parallel with that of the movable contact-member, the movable contact-member being rotatable with respect to the actuating-member.

2. An electric switch having, in combination, a plurality of fixed concentric contact-members having contact-faces lying in a common surface; a movable contact-member coaxial with said surface and having a contact-face complementary to those of the fixed contact-members; and actuating-means, connected with the middle-portion of the movable contact-member, for moving it axially toward and from the fixed contact-members, the movable contact-member being rotatable axially with respect to said actuating-means.

3. An electric switch having, in combination, a fixed contact-member; a movable contact-member; actuating-mechanism, for the movable contact-member, comprising two parts having helical connections arranged to cause the movable contact-member to move toward and from the fixed contact-member in consequence of relative rotation of said parts; and means for producing such relative rotation suddenly to cause a snap-action of the movable contact-member.

4. An electric switch having, in combination, a fixed contact-member; a movable contact-member; actuating-mechanism for the movable contact-member comprising a fixed part and a movable part having helical connections, the movable contact-member being connected with said movable part by connections permitting relative rotation of said part and said contact-member; and means for rotating said movable part on said fixed part.

5. An electric switch having, in combination, a fixed contact-member; a movable contact-member; a rotatable member for actuating the movable contact-member; and means, for imparting rapid partial rotations, in opposite directions, to said rotatable member, comprising a spring connected eccentrically to the rotatable member, and a manually-operable part connected to the spring and movable to swing the spring to opposite sides of the rotatable member.

6. An electric switch having, in combination, a casing comprising two separable

members; contact-members, and means for relatively supporting and guiding them, mounted on one casing-member; snap-action operating-mechanism mounted on the other 5 casing-member; and inter-engaging means for operatively connecting the parts mounted on the respective casing-members when said members are brought together.

7. An electric switch having, in combination, 10 a casing comprising two separable members; fixed contact-members mounted on one casing-member; a support mounted on said casing-member; a movable contact-

member associated with the fixed contact-members and supported by, and axially 15 movable upon said support; operating-mechanism mounted on the other casing-member and movable coaxially with the movable contact-member; and means, for connecting the movable contact-member and the operating-mechanism, engageable and disengageable by relative axial movement of said member and mechanism. 20
